BATH APPARATUS

John S. Martin, Atlantic City, N. J., assignor to
Hydro-Pneumatic Bath Appliance Company,
Atlantic City, N. J., a corporation of New Jersey

Application February 19, 1931, Serial No. 517,089
Renewed March 1, 1934

23 Claims. (Cl. 4—180)

This invention relates to bath apparatus, and more particularly to bath apparatus of the type employed in administering treatments that have a stimulating and healthful effect on the body of the person receiving the same.

One object of the present invention is to provide bath apparatus which is capable of producing a fluid massage on the body of a person and wherein the parts are compactly arranged in the form of a portable appliance that may be conveniently handled and readily connected with and disconnected from a source of fluid supply therefor.

Another object of the present invention is to provide a portable fluid massage apparatus or appliance which may be manufactured and sold at relatively low cost and carried about wherever desired for use in administering stimulating and invigorating hydro-pneumatic massage treatments.

Another object of the present invention is to provide a portable fluid massage apparatus or appliance which embodies flexible means adapted to conduct fluid thereto and enables said apparatus or appliance, when connected with a source of fluid, to be moved or shifted about as desired, for application of the fluid to various parts of the body.

Another object of the present invention is to provide a portable fluid massage apparatus or appliance which may be used in tubs, pools or other bathing places, through connection with fixtures therefor that are ordinarily employed to supply water or other fluid under pressure thereto.

Another object of the present invention is to provide novel manifold and injector equipment for fluid massage apparatus either of the portable type, or of the type installed in association with tubs, pools, or other bathing places or equipment.

Another object of the present invention is to provide fluid massage apparatus having an improved manifold and novel flexible connections therefor with different sources of fluid.

These and other objects of the present invention will appear as the following description thereon proceeds, and in order to more fully understand said invention, reference may be had to the accompanying drawings which illustrate several embodiments of the inventive idea.

In said drawings:

Fig. 1 is a vertical longitudinal sectional view of a tub, showing portable fluid massage apparatus embodying the present invention and connected with the hot and cold water mixing faucet for said tub;

Fig. 2 is an enlarged detail perspective view of the portable fluid massage apparatus or appliance shown in Fig. 1;

Fig. 3 is a vertical longitudinal sectional view of said apparatus or appliance;

Fig. 4 is a vertical transverse sectional view on the line 4—4 of Fig. 3;

Fig. 5 is a transverse horizontal sectional view on the line 5—5 of Fig. 3;

Fig. 6 is a vertical longitudinal sectional view of a tub equipped with fluid massage apparatus constituting another embodiment of the present invention;

Fig. 7 is a top plan view of the tub and apparatus shown in Fig. 6;

Fig. 8 is an enlarged vertical longitudinal sectional view on the line 8—8 of Fig. 7;

Fig. 9 is a fragmentary side elevation, partly in section, of a tub and fluid massage apparatus associated therewith and constituting another embodiment of the present invention;

Fig. 10 is a top plan view of parts of the apparatus shown in Fig. 9;

Fig. 11 is a vertical transverse sectional view on the line 11—11 of Fig. 10, and

Fig. 12 is an enlarged fragmentary side elevation, partly in section, of a tub and fluid massage apparatus associated therewith and constituting another embodiment of the present invention.

Referring to the drawings, wherein like reference characters designate like parts throughout the several views, Figs. 1 to 5, inclusive, illustrate a portable fluid massage apparatus or appliance embodying the present invention and including a flexible conduit 5 and a similar conduit 6 enclosed in the conduit 5 and provided with ribs 7 that hold the conduit 5 in spaced relation with the conduit 6 and form therewith channels 8 extending between and longitudinally of said conduits. The conduit 5 has one end connected, in any suitable manner, with one extremity of a sleeve 9 which is of greater diameter than the conduit 6, as clearly shown in Fig. 3 of the drawings. The conduit 6 extends into the sleeve 9 in spaced relation therewith, and said conduit has one end thereof engaged by a reduced portion 10 formed on said sleeve at the end thereof opposite that connected with the conduit 5. The conduit 6 has fitted therein adjacent the reduced portion 10 of sleeve 9, the reduced tubular extension 11 of a coupling sleeve 12 provided interiorly thereof with a rubber coupling 13 between which and the coupling sleeve 12 is arranged a screen 14. The extension 11, the adjacent end of the conduit 6, and the reduced sleeve portion 10 may, if desired, be se-

60

65

70

75

80

85

90

95

100

105

110

curely clamped together, by a suitable clamp 15 engaged thereover.

The sleeve 9 has secured to or formed integrally therewith, a tubular extension 16, and secured, 5 in any suitable manner, to said extension is one extremity of a flexible conduit 17. The opposite extremity of the conduit 17 is secured, in any suitable manner, on one end of a U-shaped tubular support 18 provided in its opposite end with a 10 screen 19.

The end of the conduit 6 opposite that connected with the coupling sleeve 12 is connected, in any suitable manner, with one extremity of a conduit 20. This conduit 20 extends longitudinally and concentrically through a conduit 21 and forms therewith a manifold, indicated broadly at 22. The end of the conduit 5 opposite that connected with the sleeve 9, is secured in any suitable manner on the end of the conduit 21 adjacent the 15 connection for the conduit 6 with the conduit 20.

Mounted on the conduit 20, and secured thereto in any suitable manner, is a washer 23 provided in the periphery thereof with a series of openings 24. This washer 23 is fitted in one end of 20 the conduit 21 and secured thereto in any suitable manner, and the openings 24 in said washer establish communication between the channels 8 and the interior of the conduit 21. The conduit 20 has fitted in the end thereof opposite that secured to the washer 23, a plug 25 which is secured to said conduit in any suitable manner. The plug 25 is secured to or formed integrally with a cap 26 that is fitted in the adjacent end of the conduit 21 and secured thereto in any suitable 35 manner. The manifold 22 extends within a guard or casing 27 secured in any suitable manner to the conduit 21, and mounted on said conduit between said guard or casing and the conduit 5, is a handle 28 of wood or other suitable material.

The manifold 22 is provided with injector means preferably comprised by a plurality of injectors indicated broadly at 29. These injectors extend transversely of the guard or casing 27 and are axially alined with openings 30 formed in a wall 31 thereof. The injectors 29 are each preferably comprised by two tubes 32 and 33 of different diameters and lengths respectively, the tubes 32 having pressed fits in suitable openings formed in the conduit 20 and the tubes 33 having pressed fits in suitable openings formed in the conduit 21. The injectors 29 serve to mix liquid and gas received from the conduits 20 and 21, respectively, and discharge jets or sprays of said mixture under pressure and at high velocity through the openings 30 in the guard or casing 27 for application to the body of a person as herein-after pointed out.

The above described portable fluid massage apparatus or appliance may be used in tubs, pools, or other bathing places as, for example, in a tub 34 such as indicated in the drawings. This tub 34 is equipped with a mixing faucet 35 for hot and cold water received from any suitable source through pipes such as indicated at 36, and said tub is provided with the usual overflow outlet 37 and drains 38, 39 the latter having therein a stopper 40. In this case, the coupling 13 of coupling sleeve 12 is connected with the faucet 35 and water under pressure is delivered through conduit 6 into the conduit 20 of manifold 22. The conduit 17, in the use of the portable apparatus or appliance as stated, is preferably supported from the upper edge of the tub 34 by the U-shaped support 18 which is engaged thereover.

The water delivered under pressure into the

conduit 20, passes through the tubes 32 and 33 of injectors 29 and is discharged therefrom through the openings 30 of guard or casing 27 into the liquid in the tub or pool 34, for application to the body of a person therein.

The water thus delivered into the injectors 29 and discharged therefrom as stated, creates suction in the member 18, conduit 17, channels 8 between sleeve 9, conduit 6, and conduit 5, and also in the conduit 21 and the nozzle 33 communicating therewith.

Air is thus drawn into the nozzle 33 through the described connections therefor with the member 18, said air being entrained and mixed in said nozzle with the water delivered therein, and the mixture being discharged from the injectors into the liquid in the tub or pool 34 for application to the body of a person therein.

The jets or sprays thus delivered from the injectors 29, when applied under water against the body of a person therein, produce a fluid vibratory massage on the body of the person with resulting invigorating and healthful effects attending the same.

At the same time, jets or sprays formed and delivered by the injectors in the liquid in the tub or pool, as described, impart a vigorous and thorough agitation to said liquid

with an accompanying restful and pleasant effect on the body of the person.

The present invention is also capable of use in other forms of appliances and equipment, and in the embodiment of said invention shown in Figs.

6 to 8, inclusive, of the drawings, a manifold, indicated broadly at 34', is secured to, and below, a perforated support 35' having openings 36' therein with which injectors, indicated broadly at 37', and secured to said manifold, are disposed in axial alinement.

The injectors 37' are disposed in spaced relation with the support 35' below the openings 36' therein, and the manifold 34' is secured to the support, as by cross members 38',

39', which are fastened in any suitable manner to said support and said manifold.

The support 35' is provided with legs 40' having cushioned feet 41 resting on the bottom of the tub 34, said legs serving to support the manifold 34' and the support 35' on the bottom of said tub in spaced

relation therewith.

The manifold 34' may be connected, as by a flexible conduit 42, with the faucet 35. For this purpose, the conduit 42 is provided at one end

thereof with a coupling 43 which may be detachably connected with said faucet. The opposite end of the conduit 42 is connected in any suitable manner with a tubular extension 44 of a manifold header 45 extending transversely of the manifold 34' at one end thereof.

This header 45 has connected therewith corresponding ends of manifold pipes or conduits 46 which extend through suitable openings formed in a manifold header 47 secured in any suitable manner to the cross member 38' on the perforated support 35'.

The opposite ends of the pipes or conduits 46 are closed by plugs 48 secured thereto in any suitable manner and formed on caps 49. The caps 49 are secured, in any suitable manner, in corresponding ends of manifold pipes or conduits 50 through which the

pipes or conduits 46 extend longitudinally thereof and concentrically therewith.

Said ends of the pipes or conduits 50 are secured in any suitable manner to the cross member 38' on the perforated support 35', and the opposite ends of the

pipes or conduits 50 are secured in any suitable manner to the header 47 in suitable openings

therein.

The header 47 has connected therewith, at one end thereof, an air pipe or conduit 51 which ex-

tends vertically to the top of the tub 34 between a side wall of the same and the support 35'. The injectors 37' are comprised by inner tubes or nozzles 52 communicating with the pipes or conduits 46 and having pressed fits in suitable openings therein, and outer tubes or nozzles 53 extending over the tubes or nozzles 52 in communication with the pipes or conduits 50 and having pressed fits in suitable openings therein. Water delivered under pressure from the faucet 35 through conduit 42 into header 45 and conduits 46, is discharged from the latter through the nozzles 52, 53 and the openings 36' in support 35', into the tub or pool 34 for application to the body of a person on said support. Suction is thus created in the pipe 51, header 47, conduits 50, and nozzles 53, so that air from the atmosphere is drawn into said nozzles through the described connections therefor with the pipe 51. Air is thus entrained and mixed with the water in the nozzles 53, and the mixture is discharged from the injectors 37', through the openings 36' in support 35', in jets or sprays which, when applied to the body of a person under water in the tub or pool 34 and positioned on said support, produce an invigorating and healthful massage, with an accompanying vigorous and thorough agitation of the water in the tub or pool and a resulting restful and pleasant effect upon the body of the person.

In the embodiment of the invention shown in Figs. 9 to 11, inclusive, of the drawings, the manifold and injectors, indicated broadly at 54 and 55, respectively, are supplied with air or other gas under pressure, instead of water or other liquid under pressure. The air or other gas under pressure may be derived from any suitable source, herein shown as a rotary compressor 56 adapted to deliver air under pressure to the manifold 54 and the injectors 55. The air inlet for the rotary compressor 56 is indicated at 57, and the driven shaft 58 of said compressor has fixed thereon a sprocket 59 around which passes a chain 60. The chain 60 also passes around a sprocket 61 which is fixed on the armature shaft 62 of an electric motor 63 which receives current from any suitable source and is controlled by any suitable type of switch (not shown). Air under pressure is delivered by the compressor 56 from the outlet 64 thereof through a pipe 65 having one end connected with said outlet. The opposite end of the pipe 65 is connected in any suitable manner with a tubular extension 66 of a manifold header 67 extending transversely of the manifold 54 at one end thereof. The manifold 54, in turn, is connected with, and supported below, a support 35' such as included in the previously described embodiments of the invention, said support resting on the bottom of the tub 34 to hold the manifold in spaced relation therewith, and the injectors 55 being disposed below the support 35' in alignment with the openings 36' therein.

The header 67 has connected therewith corresponding ends of manifold pipes or conduits 68 extending in suitable openings in said header and secured thereto in any suitable manner. The opposite ends of the pipes or conduits 68 are closed by plugs 69 secured in any suitable manner to said conduits and formed on caps 70 provided peripherally thereof with series of openings 71. The caps 70 are fitted in corresponding ends of manifold pipes or conduits 72 and secured thereto in any suitable manner, and said pipes or conduits have extending therethrough, in spaced concentric relation therewith, the pipes or conduits 68, as clearly shown in Figs. 10 and 11 of

the drawings. The opposite ends of the pipes or conduits 72 have fitted therein, and secured thereto in any suitable manner, washers or plugs 73 which, if desired, may be provided peripherally thereof with openings 73'. The pipes or conduits 68 extend through suitable openings in the washers or plugs 73 and the latter are secured in any suitable manner to said pipes or conduits.

The injectors 55 comprise inner tubes or nozzles 74 communicating with the pipes or conduits 68 and having pressed fit in suitable openings therein, and outer tubes or nozzles 75 extending over and above the inner tubes or nozzles 74 in communication with the outer pipes or conduits 72 and having pressed fits in suitable openings therein. Air or other gas under pressure delivered into the tubes or nozzles 74 through the described connections therefor with the compressor 56 is discharged from said tubes or nozzles through the tubes or nozzles 75 and the openings 36' in support 35', into water or other liquid in the tub or pool 34. The air or other gas under pressure thus discharged from the injectors 55, creates suction in the pipes or conduits 72 so that the water or liquid in the tub or pool 34 is drawn into said pipes or conduits and the outer tubes or nozzles 75, mixed therein with the air or gas under pressure, and discharged therewith as a mixture from the injectors through the openings 36' in support 35' for application to the body of a person positioned on said support in the liquid in the tub or pool. The high velocity jets or sprays thus formed and applied to the body of the person, produce an invigorating and healthful fluid massage on the body of the person, which is accompanied by a vigorous and thorough agitation of the liquid in the tub or pool imparted thereto by said jets or sprays and causing a pleasant and restful effect on the body of the person receiving the fluid massage, as aforesaid.

In the embodiment of the invention shown in Fig. 12 of the drawings, the manifold, injectors, perforated support, and mounting of the same, are the same as illustrated and described in connection with the embodiment of the invention shown in Figs. 6 to 8, inclusive, of the drawings. In the embodiment of the invention shown in Fig. 12 of the drawings, however, the water is circulated continuously in a closed circuit including the manifold 34'. Accordingly, the water or other liquid in the tub or pool 34 is withdrawn therefrom through a stand pipe 76 mounted on the support 35' over a suitable opening therein and connected with one end of a pipe or conduit 77 provided with a suitable check valve 78. The opposite end of the pipe or conduit 77 is connected with the inlet 79 of a rotary pump 80 the driven shaft 81 of which has fixed thereon a sprocket 82. Passing around the sprocket 82 is a chain 83 which also passes around a sprocket 84 that is fixed on the armature shaft 85 of an electric motor 86 supplied with current from any suitable source and controlled by any suitable type of switch (not shown). The pump 80 is thus driven through the described driving connections therefor with the motor 86, and draws water into said pump through the described connections therefor with the stand pipe 76. The water is discharged from the pump 80 through the outlet 87 thereof and a pipe or conduit 88 having one end connected in any suitable manner with said outlet. The opposite end of the pipe or conduit 88 is connected in any suitable manner with the upper end of a pipe or conduit 89 extending downwardly in the stand pipe 76 through a suitable packing gland 90

in the upper end thereof. The lower end of the pipe or conduit 89 is connected with the extension 44 of the header 45, and it will thus appear, that the water drawn from the tub 34 is circulated 5 continuously in a closed circuit including the manifold 34' and stand pipe 76, and the described connections therefor with the pump 80. The construction and operation of the embodiment of the invention shown in Fig. 12 of the drawings, is 10 otherwise the same as the construction and operation of the embodiment of the invention shown in Figs. 6 to 8 of the drawings.

It will appear, from the foregoing, that in all 15 embodiments of the present invention, water or other liquid may be delivered under pressure to the injectors thereof to entrain air or other gas therewith, or the air or other gas may be delivered under pressure to the injectors to entrain the water or other liquid therewith. It will further 20 appear, that various liquids, gases, and mixtures of the same may be employed, and that either may have as a constituent thereof, if desired, a medicinal component which may be applied to the body of the person simultaneously with the fluid 25 massage treatments. It will further appear, that in all embodiments of the present invention, the high velocity jets or sprays delivered into the liquid or water in the tub or pool, will cause a vigorous and thorough agitation of the water 30 and thus create a pleasant and restful effect on the body of the person being treated.

Several embodiments of the present invention have been herein illustrated and described more or less particularly, but it is to be expressly understood that said invention is not limited to said embodiments thereof or otherwise than by the terms of the appended claims.

What is claimed is:

1. In apparatus of the character described, a 40 guard or casing, injector means in the guard or casing and adapted to discharge a mixture of gas and liquid from said guard or casing through one or more openings therein, and flexible means secured to the injector means and including a conduit for delivering one of said fluids thereto and a second conduit adapted to be detachably connected with a source from which the other of said fluids may be delivered under pressure through the last named conduit to said injector means.

2. In apparatus of the character described, a 55 guard or casing having one or more openings in the wall thereof, one or more injector devices arranged in the guard or casing in alinement with said opening or openings and adapted to discharge a mixture of gas and liquid therethrough, and flexible means secured to the injector device or devices and including a conduit for delivering one of said fluids thereto and a second conduit adapted to be detachably connected with a source from which the other of said fluids may be delivered under pressure through the last named conduit to said injector device or devices.

3. In apparatus of the character described, a 70 manifold comprising two pipes or conduits extending one within the other, injector means mounted on the manifold and including two concentrically arranged nozzles each communicating with one of said pipes or conduits, flexible means including two tubular elements each connected with one of the pipes or conduits and adapted to deliver a fluid thereto, and means on one of the tubular elements for detachably connecting it with a source from which fluid may be

delivered under pressure through said tubular element to the pipe or conduit connected therewith.

4. In apparatus of the character described, a 80 guard or casing, a manifold therein comprising two concentrically arranged pipes or conduits extending one within the other, injector means mounted on the manifold within the guard or casing and adapted to discharge a mixture of gas and liquid through one or more openings therein, 85 said injector means including one or more pairs of nozzles alined with said opening or openings and each nozzle communicating with one of said pipes or conduits, flexible means including two tubular elements extending one within the other 90 each tubular element being connected with one of the pipes or conduits and adapted to deliver a fluid thereto, and means on one tubular element for detachably connecting it with a source from which fluid under pressure may be delivered 95 through said tubular element to the pipe or conduit connected therewith.

5. In apparatus of the character described, injector means adapted to discharge a mixture of 100 gas and liquid in liquid in a tub or pool and against the body of a person therein, a flexible conduit secured to the injector means and adapted to be detachably connected with a source from which one of said fluids may be delivered under pressure to the injector means while providing for movement of the latter as desired in the liquid in the tub or pool, and means connected with the injector means and adapted to deliver the other of said fluids thereto.

6. In apparatus of the character described, injector means adapted to discharge a mixture of 110 gas and liquid in liquid in a tub or pool and against the body of a person therein, and flexible means secured to the injector means and including a conduit for delivering one of said fluids thereto and a second conduit adapted to be detachably connected with a source from which the other of said fluids may be delivered under pressure through the last named conduit to said injector means while providing for movement of 115 the latter as desired in the liquid in the tub or pool.

7. In apparatus of the character described, injector means adapted to discharge a mixture of 125 gas and liquid in liquid in a tub or pool and against the body of a person therein, and flexible means secured to the injector means and including an outer conduit for delivering gas thereto and an inner conduit having circumferentially spaced channel forming ribs and adapted to be 130 detachably connected with a source from which liquid under pressure may be delivered through said inner conduit to said injector means.

8. In apparatus of the character described, injector means adapted to discharge a mixture of 135 air and water in water in a tub or pool and against the body of a person therein, a guard or casing carrying the injector means therein and provided with means through which the mixture of air and water may be discharged from said injector means, and flexible means secured to the injector means and including a conduit for delivering one of said fluids thereto and a second conduit adapted to be detachably connected with a source from which the other of said fluids may 140 be delivered under pressure through the last named conduit to the injector means.

9. In apparatus of the character described, a 145 plurality of injector devices each comprising a pair of concentrically arranged nozzles adapted 150

- to discharge a mixture of gas and liquid, a manifold carrying the injector devices and comprising two co-extensive concentrically arranged pipes or conduits connected with said nozzles, respectively, a guard or casing for the manifold and the injector devices and provided with openings aligned with said injector devices and through which the latter may discharge the mixture of gas and liquid, and flexible means connected with the manifold and including a tube for delivering one of said fluids to one pipe or conduit thereof and a second tube adapted to be detachably connected with a source from which the other of said fluids may be delivered under pressure through the last named tube to the other pipe or conduit. 5 80
10. In apparatus of the character described, injector means adapted to mix and discharge air and water against the body of a person, and flexible means for connecting the injector means with the atmosphere and a source of water under pressure, whereby said injector means may be moved about the body of the person as desired to discharge said mixture against various portions of the body of the person. 20 85
11. In apparatus of the character described, a guard or casing, injector means in said guard or casing and adapted to discharge a mixture of air and water therethrough against the body of a person, and flexible means for connecting the injector means with the atmosphere and a source of water under pressure, to supply the injector means with air and water and enable the guard or casing and said injector means to be moved about the body of the person as desired to discharge said mixture against various portions of the body of the person. 30 90
12. In apparatus of the character described, a manifold having concentrically arranged air and water pipes, injector devices on the manifold and each comprising two concentric nozzles communicating with the two pipes respectively, a guard or casing for the manifold and the injector devices and provided with openings through which a mixture of air and water may be discharged from said devices against the body of a person, and flexible means for connecting the manifold pipes with the atmosphere and a source of water under pressure respectively, to supply the injector devices with air and water and enable the guard or casing and the parts therein to be moved about the body of the person as desired to discharge the mixture of air and water against various portions of the body of the person. 40 95
13. In apparatus of the character described, a manifold comprising two pipes or conduits, and means adapted to mix and discharge gas and liquid received from the two manifold pipes or conduits respectively, said means comprising two tubes of different diameters extending one within the other and each communicating with one of the manifold pipes or conduits and being secured to a wall thereof independently of the adjacent manifold pipe or conduit. 50 100
14. In apparatus of the character described, a manifold comprising two pipes or conduits extending one within the other, and a plurality of means adapted to mix and discharge gas and liquid received from the two manifold pipes or conduits respectively, each of said means comprising two tubes of different diameters extending one within the other and each tube communicating with one of the manifold pipes or conduits and being secured to a wall thereof independently of the other manifold pipe or conduit. 60 105
15. In apparatus of the character described, a manifold comprising an outer pipe or conduit and an inner pipe or conduit extending therein, and means adapted to mix and discharge gas and liquid received from the two manifold pipes or conduits respectively, said means comprising two tubes of different diameters extending one within the other, one of said tubes communicating with the inner manifold pipe or conduit and having a pressed fit in an opening formed in the wall thereof and the other tube communicating with the outer manifold pipe or conduit and having a pressed fit in an opening formed in the wall thereof. 70 110
16. In apparatus of the character described, a manifold having an inner liquid conduit and an outer gas conduit in which the liquid conduit extends, and a plurality of means on the manifold for mixing and discharging gas and liquid received from the outer and inner conduits respectively, said means each comprising a pair of tubes of different diameters extending one within the other, one tube communicating with the outer gas conduit and the other tube communicating with the inner liquid conduit. 80 115
17. In apparatus of the character described, a manifold having an inner gas conduit and an outer liquid conduit in which the gas conduit extends, and a plurality of means on the manifold for mixing and discharging gas and liquid received from the gas and liquid conduits respectively, said means each comprising two axially aligned tubes of different diameters extending one within the other, one tube communicating with the inner gas conduit and the other tube communicating with the outer liquid conduit. 90 120
18. In apparatus of the character described, a manifold comprising an outer conduit having an annular member on one end thereof provided peripherally with a series of openings and an inner conduit extending in the outer conduit and on which said annular member is fitted, and means on the manifold for mixing and discharging gas and liquid each received from one of the conduits, said means comprising two tubes of different diameters extending one within the other, one tube communicating with one of said conduits and the other tube communicating with the other of said conduits. 100 125
19. In apparatus of the character described, a manifold comprising an outer conduit having an annular member on one end thereof provided peripherally with a series of openings and an inner conduit extending in the outer conduit and on one end of which said annular member is fitted, means closing the opposite ends of the conduits, and a plurality of means mounted on the manifold at intervals along the same and adapted to mix and discharge liquid and gas received from the space between the cover and the box and the interior of the latter respectively, each of said means comprising two tubes of different diameters extending one within the other, one tube communicating with the inner conduit and the other tube communicating with the outer conduit. 110 130
20. In an invigorating bath appliance in a container adapted to hold a bath fluid, a perforated element in the container, a fluid injector manifold beneath the element and having jet nozzles in pairs, each pair in register with a perforation of the element, and adapted so that one fluid of the bath may have an entraining action on another fluid of the bath, the entrained fluids 120 135
- 75 140
- 75 145
- 75 150

passing through the nozzles, thereby acting to agitate the bath fluid in the container.

21. In an invigorating bath appliance in a container adapted to hold a bath fluid, a perforated element in the container, a manifold comprising a plurality of passages arranged to cause a circuitous course, a plurality of jet nozzles communicating with said passages and registering with the perforations of the element, each jet nozzle comprising inner and outer jet tubes, the inner jet tubes for an ingredient bath fluid, the outer jet tube conducting the entrained mixture of the ingredient fluids through the perforations, such action having an entraining action on the entire bath fluid in passing through the perforations.

22. In an invigorating bath appliance in a container adapted to hold a bath fluid, a perforated element in the container, a fluid injector manifold beneath the element and having jet nozzles in pairs, each pair in register with a perforation of the element, and adapted so that one fluid of the bath may have an entraining action on another fluid of the bath, the entrained fluids passing through the nozzles, thereby acting to

25

agitate the bath fluid in the container, and means for supplying pressure to one of the bath ingredients for causing a thorough agitation of the bath fluid, thereby creating a massaging action to the bather.

23. In an invigorating bath appliance in a container adapted to hold a bath fluid, a perforated element in the container, a manifold comprising a plurality of passages arranged to cause a circuitous course, a plurality of jet nozzles communicating with said passages and registering with the perforations of the element, each jet nozzle comprising inner and outer jet tubes, the inner jet tubes for an ingredient bath fluid having an entraining action on another ingredient bath fluid, the outer jet tube conducting the entrained mixture of the ingredient fluids through the perforations, such action having an entraining action on the entire bath fluid in passing through the perforations, and means for supplying pressure to one of the bath ingredients for causing a thorough agitation of the bath fluid, thereby creating a massaging action to the bather.

JOHN S. MARTIN.
